UNITED STATES PATENT OFFICE.

JOHN LE MAY AND MILUS M. HOUSE, OF INDIANAPOLIS, INDIANA, ASSIGNEES, BY
DIRECT AND MESNE ASSIGNMENTS, TO SARGENT & COMPANY, OF NEW HAVEN,
CONNECTICUT, A CORPORATION OF CONNECTICUT.

DIE CASTING CONSTRUCTION.

1,149,842.

Specification of Letters Patent. Patented Aug. 10, 1915.

Application filed December 22, 1913. Serial No. 808,218.

To all whom it may concern:

Be it known that we, JOHN LE MAY and MILUS M. HOUSE, citizens of the United States, and residents of Indianapolis, county 5 of Marion, and State of Indiana, have invented a certain new and useful Die Casting Construction; and we do hereby declare that the following is a full, clear, and exact description thereof, reference being had to the 10 accompanying drawings, in which like letters refer to like parts.

The object of this invention is to prevent chilling of the metal before entering the dies and to simplify the sprue or means for 15 supplying metal to the die and facilitates the separation of the die member from the sprue. The first of these objects is attained by providing the die members with a hot pocket in which a large quantity of metal 20 first enters and wherein the heat is retained so that the metal passes therefrom in a molten condition through the runners to the matrices or die cavities. The other object of the invention is accomplished by 25 connecting the sprue with one of the die members so that it can be readily separated or unscrewed therefrom.

The full nature of the invention will be understood from the accompanying drawings and the following description and 30 claims:

In the drawings, Figure 1 is a central section through the device with the parts in place for die casting. Fig. 2 is a similar 35 view of the die members and an elevation of the sprue separated from the die member after the cavities in the die member have been charged with metal. Fig. 3 is a section on the line 3—3 of Fig. 2.

40 There is a sprue 10, an upper die member 11 and lower die member 12. The invention is not limited to any particular construction of sprue or other means for charging the die, but that herein shown has a conical 45 opening into which the metal is poured or discharged and through which the metal passes to the die. The lower end 13 of the sprue is reduced and externally threaded so as to screw into an internally threaded hole 50 14 in the upper die member 11 and tightly against a shoulder 15 at the inner end of said threaded hole. When the sprue is screwed into connection with the upper die member, as shown in Fig. 1, it is in commu-

nication with the upper and reduced end 55 of a substantially A-shaped cavity 16 in the upper die member, which cavity registers with a hot pocket or cavity 17 in the lower die member. This hot pocket is also slightly conical, the large end being adjacent the 60 inner surface of the lower die member and the large end of the gate or cavity 16 in the upper die member. The upper die member is provided with suitable die cavities or matrices 18 which may be formed in any 65 suitable or desired shape and which open at the inner surfaces of the upper die member. There may be any number of these die cavities 18 in either upper die member and all of them are in communication with the 70 inner hot pocket by runners or narrow passageways 19.

The die members are clamped together by any suitable means, not shown, and the metal is poured in or otherwise introduced 75 into the sprue and forced by gravity or otherwise first into the gate 16 and the hot pocket 17 and therefrom it passes through the runners 19 to the matrices 18. The pocket 17 and end gate 16 together in a 80 sense constitute the hot pocket and since the quantity of hot metal in it is relatively considerable, the metal therein does not become suddenly chilled and supplies hot metal to the runners 19 and the matrices 18. 85 The object of this invention is to bring the hot pocket for the metal close to the matrices so as to prevent the metal from chilling on its passage into the die cavities or matrices. Great difficulty has heretofore been ex- 90 perienced on account of the chilling of the metal before it reaches the die cavities because of the small capacity of the runners. By enlarging the end gate and forming a hot pocket so that a large quantity of metal 95 will be first deposited therein before it enters the matrices, this difficulty is avoided.

When the metal is cooled, the sprue 10 is unscrewed from the upper die member. The connection of the metal in the sprue 100 with that in the end gate 16 is so small that it breaks when one undertakes to unscrew the sprue. Since the metal in the end gate 16 is thrown back into the melting pot, it is immaterial how irregular the break be- 105 tween the metal in the end gate and the metal in the sprue may be. The die members are then separated and the castings

sawed away from the metal which accumulated in the runners and the metal from the hot pocket and runners thrown back into the melting pot.

- 5 By "hot pocket" herein is meant a chamber with a runner or passage leading from the upper part thereof in such position that it will never be obstructed by the accumulation of chilled material in the lower part 10 which at the beginning of each process accumulates in the lower part of the hot pocket.

The invention is:

1. In a die casting construction, die members with matrices therein, a hot pocket, and runners extending from the upper portion of the hot pocket to the matrices, substantially as and for the purpose set forth.
2. In a die casting construction, a pair of 20 die members, one of them having an end gate and a plurality of matrices, the other die member having a hot pocket registering with the end gate, and runners from the upper portion of said hot pocket to the matrices, substantially as set forth.

3. In a die casting construction, a die member with a tapering end gate, and a sprue removably secured to said die member and in communication with the smaller end of the end gate.

4. In a die casting construction, a die member with an internally threaded hole in the outer side thereof and with an end gate with a relatively small end communicating with said hole, a sprue with an externally threaded end for screwing into the hole in the die member, a plurality of matrices, the other die member having a hot pocket registering with the end gate, and runners from the upper portion of said hot pocket to the 40 matrices, substantially as set forth.

In witness whereof, we have hereunto affixed our signatures in presence of the witnesses herein named.

JOHN LE MAY.
MILUS M. HOUSE.
